ATTACHMENT FOR LOOMS

Ernest Forgea, Rensselaer, N. Y.

Application November 12, 1942, Serial No. 465,340

7 Claims. (Cl. 139—247)

This invention is an attachment for holding the yarn over the ends of bobbins which have been placed in the magazine of an automatic loom.

The type of threading attachment now in general use with automatic looms consists of a long arm which juts out from the end of the loom frame, past the magazine for the automatic bobbins. In practice, the yarns from the stacked bobbins are pulled out of the magazine and engaged with a clamp supported at the end of said arm, several feet distant from the adjacent end of the magazine. This arrangement is open to the objection that several feet of the yarn from each bobbin are immediately wasted, and to the further objection that the incident slack in the yarn makes it necessary for the operator to leave his normal position so as to pull down the yarns, thereby resulting in a substantial loss of time.

One of the objects of the present invention is to provide a threading attachment so constructed and arranged as to reduce the amount of waste yarn which results from the present day threading practice, above described. A further object is to provide a simple attachment which will make indexing of the yarns more readily threaded into the self-threading eye of the shuttle. A further object is to provide a device of the character mentioned which will serve to keep the end of the loom cleaner, and will reduce possibility of loose ends of yarn getting caught in the loom mechanism. A further object is to provide a threading attachment so constructed as to cause the yarns to automatically travel downwardly, so that it will not be necessary for the operator to pull down the yarn while operating the loom.

The invention will be hereinafter fully set forth and particularly pointed out in the claims.

In the accompanying drawing:

Figure 1 is a side elevation conventionally illustrating a standard type of bobbin magazine with the improved threading attachment secured to one end thereof. Figure 2 is an end view of Figure 1. Figure 3 is a perspective view of the detached threading attachment. Figure 4 is a perspective view of a modification. Figure 5 is a front view of a second modification.

Referring to Figures 1, 2 and 3 of the drawing, BM designates a typical bobbin magazine in which the bobbins B are stacked in a known manner commonly practiced in the art. In practice, the bobbin magazine is positioned above the lay of the loom and the shuttle box, and the front plate F thereof is provided with vertically arranged parallel guide slots F', which converge at

the lower end of the plate as indicated at F². The structure thus far described is illustrative of a type which is now in common use, the yarns from the respective bobbins being extended through the slots F', and extended to and secured to a clamp which is spaced outwardly from the magazine in a manner not shown.

The guide member G of the present invention may be constructed of any desired material, but for purposes of illustration is constructed of rather heavy stiff wire of any desired gauge. In practice, #6 (six) gauge has been found quite suitable, but the invention is not to be limited in this respect. As shown in Figures 2 and 3, the guide member G comprises two sets of strands 10 which converge downwardly and are secured together at their lower ends in suitable manner, as by soldering, indicated at 11. Arranged parallel with the strands 10 are a corresponding number of sets of outer strands 12, relatively spaced from the wires 10, and also secured at their lower ends to the strands 10 by the securing means 11. The two strands 12 are so arranged with respect to the strands 10 as to provide guide spaces 14 to receive the yarns from the bobbins. It will be noted that the upper ends of the strands 12 are free and that they are slightly divergent as indicated at 15. To the upper ends of the respective strands 10 are connected the arms 16 of a V-shaped support member having an eye 17 located at the point of the V, and so positioned as to be engageable with a face of the bobbin magazine. In practice, the guide member G is secured to the plate F by means of a bolt 18 passed through said eye 17. It will be observed that the strands 12 and their divergent portions 15 extend across the slots F' of the end plate F, so that the yarns instead of passing downwardly to the bottom of the slots F', will be diverted downwardly into the guide spaces 14. It will also be observed that the major portions of the wires 10 and 12 are approximately straight, and will be held in depending position by the support member and approximately parallel with but in spaced relationship, with respect to said face of the bobbin magazine. The lower portion of the guide member provided by strands 10 and 12 is curved from the vertical plane of said wires 10 and 12, to a position below the wires 16, so as to extend beneath the plate F and above the plane of the lay of the loom.

In practice, the bobbins are placed in the magazine in the usual way and the yarns are threaded through the slots F' into the guide spaces 14, after which they may be knotted so that they

cannot be drawn backwardly out of engagement with the guide when the bobbin is inserted into the shuttle.

In the form illustrated in Figure 4, a guide member is shown which is intended to cooperate with a single slot F' in the bobbin magazine, and embodies a structure which, in effect, corresponds to one half of the guide member of Figures 2 and 3. Referring more particularly to Figure 5, the guide consists of a single piece of wire bent to form the guide G', said guide consisting of a strand 10a and a strand 12a curved rearwardly at their lower ends and joined to provide a loop 11a. The strand 10a is provided with an inward extension 16a having an eye 17a by means of which it may be secured to the end plate of the bobbin magazine. The upper end of the strand 12a is free, and the two wires are so arranged as to provide a yarn guiding space 14a. This form of the invention is secured to the plate F in such manner that the guide space 14a registers with one of the guide spaces F' of the end plate.

In the form shown in Figure 5, a plurality of strands 10b are secured at their upper ends to a flat supporting member 16b of approximately V-shape. The strands 10 extend downwardly and are converged until their lower extremities meet. A plurality of other strands 12b are provided, they being diverged to provide four guide spaces 14b. The lower ends of the strands 10b and 12b are united in suitable manner, such for instance as by welding. The guide device of this figure is mounted upon the bobbin guide and cooperates with the latter in substantially the same manner as those illustrated in the other figures.

The advantages of the invention will be readily understood by those skilled in the art to which it belongs. For instance, by securing the guide directly to the bobbin magazine, it is necessary to draw the yarns from the bobbin magazine a very short distance, and as a result there will be a decided saving in the amount of yarn which is normally wasted in common practice because of the comparatively great distance of the yarn clamp from the bottom magazine. Also, it will be readily seen that inasmuch as the extended portions of the yarns are relatively short, and are so knotted that they cannot be drawn out of engagement with the guide, it is not only possible to keep the end of the loom clean, but also to reduce the liability of the yarn ends getting caught in the loom mechanism. Another advantage is that due to the vibration of the loom in operation, the yarns engaged with the guide spaces of the threading attachment of the present invention, will be caused to travel downwardly to the lowermost part of said guide spaces, therefore avoiding any necessity for the operator to pull down the yarns, thereby resulting in a substantial saving of time.

Having thus explained the nature of the invention and described an operative manner of constructing and using the same, although without attempting to set forth all of the forms in which it may be made, or all of the forms of its use, what is claimed is:

1. A yarn guiding attachment for the bobbin magazine of a loom comprising an approximately straight body formed of approximately parallel wire strands united at their lower ends and separated laterally at their upper ends, a support portion having means at one end to engage a surface of said bobbin magazine and having its other end connected with the upper end of one of said

parallel wires, said holding member being so located that it will support the wire strands in a depending position spaced from said surface of the bobbin magazine and approximately parallel therewith.

2. A yarn guiding attachment for the bobbin magazine of a loom comprising an approximately straight body formed of approximately parallel wire strands united at their lower ends and separated laterally at their upper ends, a support portion having means at one end to engage a surface of said bobbin magazine and having its other end connected with the upper end of one of said parallel wires, said holding member being so located that it will support the wire strands in a depending position spaced from said surface of the bobbin magazine and approximately parallel therewith, said body having a lower curved portion extended to a position beneath said support portion.

3. A yarn guiding attachment for the bobbin magazine of a loom comprising an approximately straight body formed of a plurality of sets of parallel wire strands, the wires of each set being united at their lower ends and separated laterally at their upper ends, a support member having means for engaging a surface of said bobbin magazine and other means connected with the upper end of one of the parallel wires of each set, said holding member being so located that it will support the sets of wires in a depending position spaced from said bobbin magazine surface, and approximately parallel with the latter.

4. A yarn guiding attachment for the bobbin magazine of a loom comprising an approximately straight body formed of a plurality of sets of parallel wire strands, the wires of each set being united at their lower ends and separated laterally at their upper ends, a support member having means for engaging a surface of said bobbin magazine and other means connected with the upper end of one of the parallel wires of each set, said holding member being so located that it will support the sets of wires in a depending position spaced from said bobbin magazine surface, and approximately parallel with the latter, said body having a curved portion extended to a position beneath said support member.

5. A yarn guiding attachment for the bobbin magazine of a loom comprising an approximately straight body formed of a plurality of sets of parallel wire strands, the wires of each set being united at their lower ends, a V-shaped support member having means located at the point of the V to engage a face of the bobbin magazine and having its arms respectively connected with the upper end of one of the parallel wires of each set, said holding member being so located that it will support the body in a depending position spaced from said bobbin magazine surface and approximately parallel with the latter.

6. A yarn guiding attachment for the bobbin magazine of a loom comprising an approximately straight body formed of a plurality of pairs of wire strands arranged in parallel relation and separated at their upper ends, a common means for securing the lower ends of said strands together, said sets of strands being arranged in relatively V-shaped relation, a support member having arms each connected with the upper end of one of said parallel wire strands and having a portion arranged at an angle with respect to said body to engage a surface of the bobbin magazine, said support member being so located that it will hold said body in depending position from

said surface and approximately parallel with the latter, said body having a lower curved portion extended to a position beneath said support portion.

7. A threading attachment for looms comprising a wire body having two downwardly converging strands connected at their lower ends, a support member connecting the upper ends of said

strands, and two guide strands parallel with but separated from the first mentioned respective strands so as to provide yarn-guiding spaces, said guide strands being secured at their lower ends to the first mentioned strands and free at their upper ends.

ERNEST FORGEA.
